INVENTOR

Morgan L. Greer,

BY Richard Oliver,

ATTORNEY

UNITED STATES PATENT OFFICE.

MORGAN L. GREER, OF MYRA, KENTUCKY.

AUGER.

1,262,328.

Specification of Letters Patent.

Patented Apr. 9, 1918.

Application filed June 21, 1917. Serial No. 176,199.

To all whom it may concern:

Be it known that I, MORGAN L. GREER, a citizen of the United States, residing at Myra, in the county of Pike and State of Kentucky, have invented certain new and useful Improvements in Augers, of which the following is a specification.

This invention has relation to augers or drilling devices, and has for an object to provide a portable device adapted to be held against the breast and including an auger and gearing manually operable to rotate the auger.

Another object of the invention is to provide a drilling device having the above named characteristics and embodying a rest of a novel construction permitting the device to be held against the breast of the operator and to provide for comfort and to relieve pressure on the breast while the machine is being operated.

A still further object of the invention is to provide a breast drill of an extremely simple construction embodying few parts permitting the device to be economically manufactured.

In addition to the foregoing my invention comprehends improvements in the details of construction and arrangement of the parts to be hereinafter more fully described and particularly set forth in the appended claim.

In the accompanying drawings in which similar and corresponding parts are designated by the same characters of reference throughout the several views in which they appear:

Figure 1, is a view in front elevation of an auger constructed in accordance with my invention, and

Fig. 2, is a view thereof in edge elevation.

With reference to the drawings, 10 indicates generally the frame of my improved auger, comprising parallel side strips 11 of resilient material, connected at one end by means of an integrally formed connecting bar 12, a second connecting bar 13 spaced inwardly from said bar 12, and a third bar 14 spaced from said bar 13 defining a space 50 between said bars 13 and 14 in which to inclose the gearing to be described. The opposite ends of the side strips 11 are formed with eyes 15 coacting with leaves 16 forming a hinge joint, the eyes and said leaves being connected

by means of pintles 17 to provide for relative movement of the leaves and the ends of said side strips. A rest 18 is provided comprising strips 19 connected at meeting ends by means of a hinged joint 20 whereby to dispose said members 19 in alinement. 55 The leaves 16 are secured to the sides of the members 19 at points adjacent the free terminals thereof which free terminals are curved as at 20 to engage around the sides of the body when the rest 18 is applied to 60 the breast during operation of the device. It is to be noted that the side strips 11 between the cross bar 14 and the terminals of said strips are sufficiently long to permit flexing of said side strips, and with 65 this object in view the strips should be made of some resilient material.

A drive shaft 21 is mounted to extend transversely of the side strips 11, and is located between the cross bars 13 and 14 and 70 journaled in the side strips as indicated. The terminals of the drive shaft are squared to receive the crank arm 22 having perforated enlargements at one end to receive the squared portions of the drive shaft, and 75 hand grips 23 swiveled upon the arm whereby the grips may be grasped and the drive shaft readily rotated. A bevel gear 24 is mounted upon said shaft in fixed relation thereto for meshing engagement 80 with a second bevel gear 25 mounted upon the inner end of a driven shaft 26 which extends longitudinally of the device or midway between the strips 11 in parallel relation thereto with one end of said 85 driven shaft journaled in the cross bar 13, and the other end journaled in the cross bar 12. A socket 27 is formed upon the outer end of said driven shaft to receive the tang 90 28 of an auger indicated at 29.

In use, the rest portion 18 is applied to the breast of the operator and the grips of the crank arms grasped in each hand and said crank arms rotated whereupon the motion of the drive shaft will be communicated through the gears 24 and 25 to the auger to rotate the same. This tool is designed especially for use in coal mining for drilling holes for blasting, although it will be obvious that its uses may extend to other industries and find other applications therein. 95 100 105

It is to be noted that when the device is pressed against the breast of the operator,

the rest portion 18 will yield owing to the hinged joint 20' therein, such movement however being resisted by the strips 11 which are resilient and which will offer a cushioning effect to prevent discomfort to the user of the device by the pressure required to be exerted upon the device when in use.

While I have illustrated and described my invention with some degree of particularity, I realize that in practice various alterations thereover may be made, and I therefore desire to reserve the right and privilege of changing the form of the details of construction or otherwise altering the arrangement of the correlative parts without departing from the spirit of the invention or the scope of the appended claim.

Having thus described my invention, what

I claim as new and desire to secure by Letters Patent is:

In an auger, a frame including parallel resilient side members, cross bars connecting said members, and a breast plate formed of pivoted sections, each section being pivotally connected to one of the side members of the frame whereby the members of the breast plate are normally retained in alignment but are relatively movable, such movement being resisted by the side member of the frame.

In testimony whereof I affix my signature in presence of two witnesses.

MORGAN L. GREER.
